Term of patent 14 years

Int. Cl. D3—99

U.S. Cl. 87—1

FIG. 2.

FIG. 4.

FIG. 1 is a top left end perspective view of my new design for a drill case;

FIG. 2 is a top plan view of the drill case of FIG. 1;

FIG. 3 is a bottom right end perspective view of the drill case of FIG. 1; and

FIG. 4 is a front elevation view of the drill case of FIG. 1.

The top of the lid and the rear of the drill case are substantially plain and unornamented while the left interior drill holder is identical in appearance to the right interior drill holder as shown in FIG. 1.

I claim:

The ornamental design for a drill case, as shown and described.
